UNITED STATES PATENT OFFICE.

CYRA B. WATTLES, OF PROVIDENCE, RHODE ISLAND.

FLOOR-DRESSING MACHINE.

No. 820,751.

Specification of Letters Patent.

Patented May 15, 1906.

Application filed July 20, 1903. Serial No. 166,395.

To all whom it may concern:

Be it known that I, CYRA B. WATTLES, a citizen of the United States, residing at Providence, in the county of Providence and State 5 of Rhode Island, have invented a new and useful Improvement in Floor-Dressing Machines, of which the following is a specification.

This invention has reference to an improvement in floor-dressing machines used for surfacing, finishing, and polishing wood floors.

In the use of floor-dressing machines on wood floors it is essential that the weight or pressure of the dressing-roller when covered 15 with an abrasive material, such as sandpaper, should be adjustable. When the floor is of soft wood, such as pine, the pressure of the dressing-roller should be less than that required when the floor is of hard wood, such as 20 oak or maple.

In the use of the machine for polishing the floor the roller is covered with a polishing material, such as a cloth having a loop pile or nap. When the machine is used for polishing, it is important that the roller should be 25 adjustable from the floor so that the pile or nap of the cloth only is in contact with the floor.

The object of my invention is to improve 30 the construction of a floor-dressing machine whereby the pressure of the dressing-roller on the floor is adjustable, the dressing-roller is adjustable from the floor when used in polishing, the belt connecting the motor of the machine with the dressing-roller is adjusted, and a more compact machine is constructed.

My invention consists in the peculiar and novel construction of a floor-dressing machine having mechanism for adjusting the 40 pressure of the dressing-roller on the floor, for adjusting the roller from the floor when used for polishing, and for adjusting the motor on the frame of the machine, to adjust the belt connecting the motor with the dressing- 45 roller, as will be more fully set forth herein-after.

Figure 1 is a side view of my improved floor-dressing machine in its operative position on the floor. Fig. 2 is a plan view of the 50 improved floor-dressing machine, showing the motor adjustably secured on the frame of the machine. Fig. 3 is an enlarged sectional view taken lengthwise through the machine, showing the motor and handle broken away. Fig. 4 is a transverse sectional view taken on

line X X of Fig. 3, showing the adjustable axle supporting the wheels at the rear of the machine. Fig. 5 is a detail view showing the means for adjustably securing the axle in the frame to vary the weight or pressure on the 60 dressing-roller; and Fig. 6 is a detail view, partly in section, or the end of one of the forward arms for supporting the dressing-roller, showing one of the rubber buffers secured in the end of the arm to prevent the machine 65 when in use from injuring the base-board of a room.

In the drawings, *a* represents the frame of the machine, supported on the floor by the wheels *b b* and the dressing-roller *c*; *d*, the 70 hollow T-shaped handle, pivotally secured at its lower end to the frame; *e*, the flexible electric cable, connecting with the handle; *f*, the electric motor, adjustably secured to the frame; *g*, the belt connecting the motor 75 with the dressing-roller, and *h* the adjusting-caster for adjusting the dressing-roller from the floor when used for polishing. The frame *a* has the sides *a' a'* extending outward at the front to form the arms *a² a²*, 80 in which are the bearings *a³ a³* for the shaft of the dressing-roller *c* and the cavities *a⁴ a⁴* in the ends of the arms for the rubber buffers *a⁵ a⁶*. In the sides *a' a'* of the frame are the elongated openings *a⁸ a⁸*, and extending outward from the sides at the ends of the openings are the lugs *a⁷ a⁷* for the adjusting-bolts *a⁸* 85 *a⁸* in screw-thread engagement with the lugs. The wheels *b b* are rotatably secured on the ends of the axle *b'*, which extends through 90 the openings *a⁸ a⁸* in the frame and is adjustably secured by the bolts *a⁸ a⁸*.

The dressing-roller *c* is covered with an abrasive or polishing material, such as sandpaper or cloth, and is revolved by the pulley 95 *c²* on the outer end of the dressing-roller shaft *c'* in the bearings *a³ a³*.

The electric motor *f* with the pulley *f'* has the base *f²* with the slots *f³ f³* adjustably secured to the frame *a* by the bolts *f⁴ f⁴*, extending through the slots into the frame *a*. The motor is adjusted lengthwise on the frame *a* by the adjusting-bolts *a⁹ a⁹* in screw-thread engagement with the lugs *a¹⁰ a¹⁰* (forming a part of the frame *a*) and engaging 105 with the base of the motor. The motor *f* is preferably a self-contained motor, such as an electric motor, and derives its power from a source of electric energy through the wires in the flexible cable *e*. These wires extend 110

downward through the hollow T-shaped handle d , connecting with the switch d' , placed on the handle in a convenient position for the operator and leaving the handle near 5 its lower end through the aperture d^2 connect with the motor f in the usual way. The motor has sufficient power to revolve the dressing-roller on the floor at a high rate of speed through the pulley f' , the belt g , and the pulley c^2 on the dressing-roller shaft, while the operator moves the machine on the floor by 10 the handle d , the lower end of which abutting against the framework of the machine below the point of pivotal connection thereto 15 enables the operator by depressing the handle, to lift the dressing-roller from the floor when desired. The adjusting-caster h has the screw-threaded stem h' , extending upward through the cylindrical boss a^{11} , forming a part of the 20 frame a , and is adjustably secured in the boss by the nuts $h^2 h^2$ in screw-thread engagement with the stem h' of the caster.

The pressure required on the dressing-roller c is secured by adjusting the position of 25 the wheels b b lengthwise of the machine, bringing the weight of the motor f more or less on the dressing-roller. The tension required on the belt g is attained by adjusting the motor f on the frame a , and the roller c 30 is adjusted when used for polishing by adjusting the caster h to engage with the floor and raise the roller from the floor the distance required, the machine now being supported on the wheels b b and the caster h .

35 It is evident that any well-known means for transmitting power from the motor to the dressing-roller could be used and that any form of motor having the adaptability may be used without materially affecting the 40 spirit of my invention.

Having thus described my invention, I claim as new and desire to secure by Letters Patent—

1. In a floor-dressing machine, a motor 45 transmitting power to a dressing-roller, and means consisting of mechanism for adjusting the weight of the machine horizontally with respect to the dressing-roller to put more or less weight on the dressing-roller to vary the 50 pressure of the dressing-roller on the floor, for the purpose as described.

2. In a floor-dressing machine, a frame supporting a motor and a dressing-roller, means for transmitting power from the motor 55 to the dressing-roller, consisting of pulleys on the shafts of the motor and dressing-roller connected by a belt, and means for adjusting the weight of the motor upon the dressing-roller, consisting of mechanism adapted to 60 adjust the motor on the frame horizontally toward or from the dressing-roller, as described.

3. In a floor-dressing machine, the combination with a frame, a pair of wheels therefor, a dressing-roller mounted in said frame

on a horizontal axis and forming with said wheels, the sole support of the machine, a self-contained motor mounted upon the frame for driving said roller, and means consisting of mechanism for adjusting the weight 70 of the machine with relation to the dressing-roller to place more or less weight on the dressing-roller whereby to proportion the weight of the machine to be supported by the wheels and said roller for the purpose specified. 75

4. In a floor-dressing machine, a frame, wheels adjustably secured to the frame, a dressing-roller rotatably secured in the frame and adapted to engage with the floor, a motor on the frame, a handle pivotally secured to the frame, pulleys on the shafts of the motor and dressing-roller connected by a belt, a caster adjustably secured in the frame and adapted to engage with the floor, means for 80 adjusting the pressure of the dressing-roller on the floor, consisting of mechanism adapted to adjust the position of the wheels on the frame, means for adjusting the tension of the belt, consisting of mechanism adapted to adjust the position of the motor on the frame, means for adjusting the dressing-roller from the floor, consisting of mechanism adapted to 85 adjust the caster in the frame, to bring the caster into engagement with the floor, and means for transmitting power from a source of energy to the motor, as described. 90

5. In a floor-dressing machine, the combination of the frame a supported on the floor by the wheels b b adjustably secured to the 100 frame, and the dressing-roller c rotatably secured in the frame, of the hollow T-shaped handle d pivotally secured at its lower end to the frame, the flexible cable e having wires extending downward through the handle connecting with the switch d' on the handle and to the motor f adjustably secured on the frame a by the bolts $f^4 f^4$ and $a^9 a^9$, the pulleys f' on the motor connected to the pulley 105 c^2 on the dressing-roller shaft c' by the belt g and the caster h having the screw-threaded stem h' extending upward through the boss a^{11} on the frame a and adjustably secured in the boss by the nuts $h^2 h^2$ in screw-thread engagement with the stem h' , as described. 110

6. In a floor-dressing machine, the frame a having the sides a' a' extending outward at the front to form the arms $a^3 a^2$ in which are the bearings $a^3 a^3$ for the shaft of the dressing-roller c and the cavities $a^4 a^4$ for the rubber 115 buffers $a^5 a^5$, the elongated openings $a^6 a^6$ in the sides a' a' , the outwardly-extending lugs $a^7 a^7$ on the sides at the ends of the openings, the adjusting-bolts $a^8 a^8$ screw-threaded in the lugs for adjusting the position of the 120 wheels b b rotatably supported on the axle b' extending through the openings $a^6 a^6$ in the sides a' a' , the adjusting-bolts $a^9 a^9$ in screw-thread engagement with the lugs $a^{10} a^{10}$ on the frame a and engaging with the base f^2 of 125 130

the motor *f* and the cylindrical boss *a*¹¹ in which the caster *h* is adjustably secured, as described.

7. In a floor-dressing machine, the combination of a frame, a dressing-roller mounted in one end of the frame on a horizontal axis and extending across the longitudinal middle line of the machine and serving as a support for that end of the frame, a pair of wheels secured near the opposite end of the frame, said wheels and dressing-roller forming the sole support of the frame, an electric motor mounted on the frame and connected to the dressing-roller to rotate the same, and means for connecting the motor with a source of electric energy.

8. In a floor-dressing machine, the combination of a frame, a pair of wheels therefor, a dressing-roller mounted in said frame on a horizontal axis and forming with said wheels, the sole support of the machine, a self-contained motor mounted on the frame for driving said roller, means for relatively adjusting the weight of the machine with respect to said supports whereby the pressure of the dressing-roller on the floor may be varied, and a handle pivotally secured to the frame and abutting thereagainst below its pivotal

connection thereto, whereby the operator may at will lift the dressing-roller from the floor.

9. In a floor-dressing machine, the combination with a frame, a pair of supporting-wheels therefor, a dressing-roller mounted in said frame and forming with said wheels the sole supports of the machine, a self-contained motor mounted on the frame for driving said roller and means for relatively adjusting the weight of the machine with respect to said supports whereby the pressure of the dressing-roller upon the floor may be varied.

10. In a floor-dressing machine, a motor transmitting power to a dressing-roller, and means consisting of mechanism for adjusting the weight of the motor in relation to the dressing-roller to give more or less weight on the dressing-roller to vary the pressure of the dressing-roller on the floor, for the purpose as described.

In testimony whereof I have signed my name to this specification in the presence of two subscribing witnesses.
